UNITED STATES PATENT OFFICE.

FRANK A. HAYS, OF PHILADELPHIA, PENNSYLVANIA.

DESIGN FOR A PATTERN FOR DOLLS.

40,749.

Specification for Design. Patented June 28, 1910.

Application filed June 23, 1909. Serial No. 503,964. Term of patent 3½ years.

To all whom it may concern:

Be it known that I, FRANK A. HAYS, a citizen of the United States, residing at Philadelphia, in the county of Philadelphia, State of Pennsylvania, have invented a new, original, and ornamental Design for a Doll.

The design is illustrated in the accompanying drawing in which the figure shows a face elevation of a doll pattern.

I claim:

The ornamental design for a pattern for a doll as shown.

FRANK A. HAYS.
